[57] ABSTRACT

An independent assembly for holding and mixing concrete comprises a mixing drum, power drive means for rotating the drum, a base support member to which the drum and drive means are secured, and hydraulic lift means for raising and lowering the base support member. A plurality of independent assemblies, once filled with concrete are directed to a distribution area or jobsite by a single truck having an extended chassis on which a first one of the filled assemblies is secured and pulling one or more additional trailers on which others of the assemblies are secured. At the jobsite the trailer mounted assemblies are dropped off and the truck advances around the area discharging the concrete. Thereafter, the empty assembly is elevated by a hydraulic lift means, disengaged from the truck chassis and one of the filled assemblies is then secured on the truck and the concrete discharged.

**CONCRETE HOLDING AND MIXING ASSEMBLY
AND METHOD OF TRANSPORTING AND
DISTRIBUTING CONCRETE**

BACKGROUND OF THE INVENTION

Truck mixers for transporting and delivering ready mix concrete to a jobsite are well known and have been extensively used for that purpose. These units comprise a truck or transport vehicle having an extended chassis on which mixer drum assemblies are secured. These units normally are capable of carrying between about 6 and about 9 yards of ready mix concrete. Although such truck mixers are very useful for transporting and discharging the concrete at the specific desired location, they are limited in the amount of concrete which can be carried at one time. Thus, being so limited since only a single mixer drum assembly can be secured on a truck, it must make repeated trips between the concrete batch plant and jobsites or a plurality of trucks must be used in order to deliver a specific larger required amount of concrete. Although larger truck mixers have been proposed, the chassis of a truck or transport vehicle is limited by the weight that it can carry which in turn inherently limits the load capability and capacity of the mixer drum. Moreover, extremely heavy loads on a single transport vehicle chassis may exceed weight limits on roads and highways. Further, although semi-trailers for carrying larger loads are available, for example, twelve yard trailer mixers, such rigs are usually unsuitable because of difficult handling characteristics in discharging the concrete at specific locations on jobsites and particularly where the distribution space is somewhat limited. It is to the elimination of these disadvantages and especially the limitation of the amounts of concrete that a single truck or transport vehicle may haul to a jobsite that the present invention is directed.

SUMMARY OF THE INVENTION

It is an object of the present invention to provide an independent mixer assembly which may be raised and lowered, mounted on a truck chassis or full trailer and easily removed therefrom as desired. It is a further object of the invention to provide a method for transporting significantly greater amounts of ready mix concrete to a jobsite by a single truck, tractor or transport vehicle than has been previously possible. It is a further object of the invention to provide a method of delivering and discharging the concrete from the independent mixer units at the jobsite without any additional equipment other than the truck or transport vehicle. These as well as other objects will be evident from the detailed description following.

The present invention resides in an independent concrete mixer assembly which includes a drum, power means for rotating the drum (to maintain ready mix concrete in a fluid state), a base support member in which the drum and the power means are secured, and hydraulic lift means for raising and lowering the support member and drum. This assembly may be secured to either a full trailer or truck chassis for transporting the concrete from a source point such as a batch plant to a jobsite.

Utilizing the mixing assembly of the invention, after being filled to the desired extent with concrete, one of the assemblies is secured to a truck chassis and another assembly to a full trailer which trailer is then attached

to the truck for being pulled. Once at the jobsite, the full trailer is disengaged and the truck mixer, which includes the truck and first mixer assembly, is driven around the jobsite while the concrete is discharged as and where desired. The truck is then driven to the location of the trailer, reconnected thereto and the full mixer assembly is elevated by hydraulic lift means from the trailer bed to be free standing. The truck is pulled forward some distance leaving the full standing assembly behind. After stopping the truck, the empty assembly is elevated from the truck chassis and the truck and trailer pulled forward until the empty assembly is directly over the trailer, where it is then lowered and secured. The trailer is then disconnected from the truck chassis and the truck is backed under the full or loaded assembly where it is lowered and secured. The concrete may also then be discharged at the jobsite as and where desired.

BRIEF DESCRIPTION OF THE DRAWINGS

FIG. 1 is a side view illustrating the mixer assembly of the invention;

FIG. 2 illustrates two mixer assemblies of FIG. 1, one on a truck chassis and the other on a full trailer for being transported;

FIG. 3 illustrates a mixer assembly which has been raised for being secured to or removed from a truck chassis; and

FIG. 4 is an end view of the base support member showing a horizontal hydraulic ram embodiment.

DETAILED DESCRIPTION OF THE INVENTION

Referring initially to FIG. 1, there is shown a mixer assembly 10 having a mixer drum 20 secured to a base support platform 14. The assembly includes a motor 24 for driving drum 20 rotationally in two directions, one direction for mixing the other for discharging. The motor is included in this power drive means for rotating the drum as are a fuel supply for the motor and drive gears to the drum as will be appreciated. A water tank 22 is also required on an independent mixer unit for providing water to be added to the drum during the mixing operation to maintain concrete in a desirable fluid condition. Thus, water supply lines to the drum interior, drains, nozzles and the like will also be present. The water tank may be of the pressure type or provided with a pump.

The mixer drum which includes internal mixing and discharge blades is also provided with a hopper into which concrete is loaded into the drum. A chute 19 which may include extensions and multi-position locks so that concrete may be discharged from the mixer at any desired location, on either side of the truck. A control assembly panel 26 is also provided at any convenient location to allow the operator to control the mixer assembly outside of the truck cab. Other equipment may also be provided on the assembly as desired.

Means for raising and lowering the assembly comprises a hydraulic lift or ram 16 having a piston rod 18 extending therefrom and a plate 17 at the lower end of the piston rod. The purpose of the hydraulic ram, which will of course be present at all four corners of base support member 14, is for elevating and lowering the support member and, of course, the entire mixer assembly. When this is to be accomplished, an operator may raise and lower the assembly through this hydraulic lift means by extending piston rods 18 to any desired

extent inwardly or outwardly from hydraulic ram 16 as desired. Preferably, a lever for this is provided on control panel 26 and all four rams should work simultaneously so that the exposed piston rods will extend substantially equally. A safety device or mechanism for maintaining all of the vertical rams in an extended position when the assembly is free standing and preventing tipping in case of hydraulic pump failure may also be incorporated.

A signal device may be used for informing the operator in the truck cab when the truck chassis or trailer bed is in proper position relative to the assembly. Such a device will be of great assistance to the driver giving him warning when he should stop the truck when pulling forward or backing under an assembly. Any means may be used such as a spring loaded two way switch in an electrical circuit having a light or buzzer alarm, one or two switches installed on the truck or trailer at a suitable position for being contacted by the assembly to close the circuit.

A further embodiment is illustrated in FIG. 4 providing a horizontal hydraulic ram 28 and cooperating with piston rod 29. The purpose for this horizontal ram, again which is on all four corners of base support member 14, allows for clearance of the tires and wheels of a full trailer or truck chassis. In other words, where the wheels or tires of a trailer or truck extend laterally to such an extent that they would interfere with or contact ram 16 when in location such as shown in FIG. 3, the vertical lift means must be extended somewhat horizontally and outwardly to provide necessary clearance so that a truck or trailer can be pulled away from the device as shown. Accordingly, the embodiment illustrated in FIG. 4 wherein hydraulic ram 28 and piston rod 29 will extend ram 16 and piston rod 18 horizontally to a desired extent to provide necessary clearance for the wheels and tires, a truck chassis or trailer can be readily placed under or pulled away from the assembly for the purpose as will be further explained herein-after.

The method of using the assembly of the invention in transporting concrete to a jobsite and there distributing it is as follows:

Two or more assemblies as shown in FIG. 1 are filled to any desired extent with ready mix concrete at the batch plant or other source point. It will be understood that the desired amount of concrete is placed in mixing drum 20 of each assembly and the power means or motor for rotating the drums are started at any desired rate. It will be understood by those skilled in the art that until the concrete has been completely distributed and discharged from the drum, some drum turning is required at all times in order to maintain concrete in a fluid state and prevent it from setting up. The drum may be filled while the assembly is maintained in a stationary location as illustrated in FIG. 1 or the assemblies may be secured to a truck and full trailer as shown in FIG. 2 and transported to the concrete supply point where the drums are filled. It will be noted that when the assemblies are secured to the extended truck chassis and full trailer respectively, the pistons have been drawn into the hydraulic rams so that the full weight of each assembly rests on the truck or trailer as shown.

An operator will transport the filled assemblies to a jobsite with the truck 15 carrying mixer assembly 11 while full trailer 32, connected to the truck, carrying the assembly 21. It should be appreciated that this lat-

ter assembly will have its own independent drum rotating means and providing whatever power necessary for that purpose independent of the truck 15.

Once the operator has transported both of these assemblies to a jobsite, trailer 32 is disconnected from the truck and it and mixer assembly 21 will be moved to some desirable location while the operator transports assembly 11 around the jobsite distributing and discharging the concrete to desired locations. Once the drum of assembly 11 has been emptied, the operator will transport it to the location of trailer 32 and reconnect the trailer to the truck. Thereafter, he will actuate hydraulic rams 16 of the full assembly 21 to extend piston rods 18 to a position as shown in FIG. 1 so that it will be free standing from the trailer. Moreover, if required to provide clearance for the tires of the trailer the horizontal extending hydraulic rams 28 may be actuated as shown in FIG. 4. Thereafter the truck and attached trailer are pulled forward so that the trailer is removed from under the full assembly. The truck is stopped and the empty assembly disconnected and elevated to a free standing position as described regarding assembly 11 and shown in FIGS. 1 and 3. The truck is then driven straight forward until the trailer is directly beneath the empty assembly which is then lowered and secured on the trailer. Thereafter the trailer is disconnected and the truck driven to the free standing full assembly, where it is backed into position as shown in FIG. 3. The assembly is then lowered on the chassis and secured and the vertically extending hydraulic rams are retracted so that the truck now supports the full weight of the assembly. The operator then again transports the concrete around a jobsite and discharges it at desired locations. Once this second assembly and mixer drum have been emptied, the driver may return to the first emptied assembly, secure it to the trailer 32 and transport both mixer assemblies back to the concrete loading point where they may be again filled if desired. The sequence described in exchanging the full assembly for the empty one is preferred since it will be appreciated that it is most difficult to back a trailer precisely under a free standing assembly where the clearance of wheels and tires thereunder are quite small. Thus, for example, the operator could remove the filled assembly from the trailer prior to reconnecting the truck. Such variations in sequence of steps in exchanging a loaded assembly on the truck chassis for an empty one within the purview of the invention will be understood by those skilled in the art.

It will be appreciated that although the above method has been described with two mixer assemblies, three or more of such assemblies may be utilized. It will be understood that for each additional mixer assembly, another full trailer will be required and these trailers may be pulled in tandem by the truck. The only limitation, of course, is the number of such trailers and full assemblies the truck is capable of pulling. Regardless of how many assemblies are pulled to a jobsite by a single truck, it will be understood that the operator simply needs to park the filled assemblies while the concrete in the assembly which has been secured to the truck chassis is distributed at the jobsite. Thereafter, the operator extends the hydraulic rams so that the truck is removed from the assembly at any desirable location. The truck then proceeds to one of the filled mixer assemblies, the trailer is removed and the assembly secured to the truck chassis as previously explained. It will be understood that the present invention offers dis-

tinct advantages over prior art methods of transporting and distributing concrete where single trucks transport only single mixer units which obviously limits the amount of concrete which can be transported by one trip of the truck. This as well as other advantages and embodiments within the purview of the invention will be evident to those skilled in the art.

In another embodiment of the invention, the assembly may be provided with a conveyor belt or other means for transferring a portion or all of the cement in a filled drum to an empty drum. For example, observing FIG. 2, assembly 21, if provided with a conveyor, could be used to transfer a portion of its concrete to assembly 11 by backing truck 15 up to the unit so that concrete could be transferred without exchanging assemblies as previously disclosed. The conveyor would be used to carry concrete discharged from assembly 21 (from the chute) to the hopper of assembly 11. This embodiment would be useful if only a portion of the concrete from assembly 21 were required to complete 20 a job and may save time in transferring the concrete portion rather than exchanging assemblies from trailer to truck.

I claim:

1. An assembly independent from a truck chassis or 25 trailer frame for holding and mixing concrete comprising: a mixing drum, power drive means for rotating said drum, a base support member to which said drum and drive means are secured, and hydraulic lift means for selectively raising and lowering said base support member and being extendable to support said assembly on a ground surface and retractable to lower said assembly for being mounted on a truck chassis or trailer.

2. The assembly of claim 1 wherein said lift means comprises a plurality of hydraulic rams. 35

3. The assembly of claim 2 including a plurality of

horizontally extendable members to which said hydraulic rams are attached.

4. The assembly of claim 3 wherein said extendable members are hydraulically operated.

5. The assembly of claim 2 wherein said frame has four corners and said hydraulic rams are secured adjacent said corner for simultaneously raising and lowering said corners to maintain said support member substantially horizontal.

10 6. The assembly of claim 1 including chute means for delivering concrete from said drum.

7. A method of transporting and distributing concrete comprising:

a. filling a plurality of independent concrete holding and mixing assemblies of claim 1;

b. securing a first one of said assemblies on a truck chassis and securing each of the others of said assemblies on a towing trailer;

c. connecting said towing trailers in tandem to said truck trailer and towing said assemblies to a distribution area with said truck;

d. disengaging said towing trailers and distributing concrete from first assembly until said drum is emptied;

e. elevating said full assembly from said trailer by said hydraulic lift means, and reconnecting the trailer to the truck, pulling the trailer from under the full assembly, elevating the empty assembly and securing it to the trailer, disconnecting said trailer and moving said truck from said emptied assembly and trailer to said full assembly and securing it thereto; and

f. distributing concrete from said other full assembly till emptied and repeating step (e) till all of the full assemblies are emptied.
